UNITED STATES PATENT OFFICE.

MICHAEL REDLINGER, OF FREEPORT, ILLINOIS, ASSIGNOR TO THE DEVORE & HENNEY COMPANY, OF SAME PLACE.

FOOT-POWER HAMMER.

SPECIFICATION forming part of Letters Patent No. 417,201, dated December 10, 1889.

Application filed July 11, 1889. Serial No. 317,127. (No model.)

To all whom it may concern:

Be it known that I, MICHAEL REDLINGER, a resident of Freeport, in the county of Stephenson and State of Illinois, have invented 5 certain new and useful Improvements in Foot-Power Hammers; and I do hereby declare the following to be a full, clear, and exact description of the invention, such as will enable others skilled in the art to which it 10 pertains to make and use the same.

My invention relates to improvements in foot-power hammers, and is fully described and explained in this specification and shown in the accompanying drawings, in which—

15 Figure 1 is a perspective view of a hammer embodying my invention. Fig. 2 is a view of the hammer-head, partly in side elevation and partly in vertical section. Fig. 3 is a horizontal section through the line X X, Fig. 1, 20 and illustrates the connection of the main standard and the hammer-supporting bracket. Fig. 4 is a vertical longitudinal section of the pivoted block which supports the hammer-handle, the plane of the section being through 25 the line Z Z, Fig. 5. Fig. 5 is a transverse section of said block, the plane of section being through the line Y Y, Fig. 4. Fig. 6 is a side elevation of the block which supports the operating-lever, a portion of the block 30 being broken away to show its internal construction.

In the views, A is a standard or column, of any desired form, provided with a suitable base, and formed near its upper end with a 35 cylindrical neck a, above which is a head for the adjustment of one of the members f' of a two-part die. The standard A supports a horizontal bracket B, formed, preferably, of a single bar of iron, bent at its center in a cylindrical curve b, Figs. 1 and 3, conforming to the 40 surface of the cylindrical neck of the standard, the two ends of the bar being extended from said central curve a suitable distance and at a suitable angle to give the bracket 45 the necessary size and strength. Upon the outer end of the bracket thus formed is rigidly mounted a transverse head C, formed with upwardly-extending arms c and downwardly-extending-arms c', adapted to support the 50 oscillating parts of the device. Between the ends of the upper arms c of the head is pivoted a block D, having preferably non-cylindrical

lateral extensions d, the pivoting of said block being accomplished in any desired manner, but preferably by means of coned 55 pointed centers N, passing through the ends of the arms C and entering corresponding sockets in the block D or its extensions d. The block D receives and supports one end of a hammer-handle E, of any suitable form, 60 but preferably made up of a single bar of steel E, bent at its center to form a circular curve e, Fig. 2, the two equal parts of the bar being substantially parallel, and their ends being secured in the block D in the manner 65 hereinafter described.

On the free end e of the hammer-handle is hung the hammer F, provided at its lower end with means for attaching the upper member f of the two-part die, the curved end e of the handle being seated in a socket F', open on the side of the hammer toward the supporting block D, the inner end of the socket being a curve corresponding substantially to the outer surface of the curved end of the 75 handle. A transverse slot F'' passes through the hammer from side to side, the central plane of the slot being coincident with the diameter of the curve forming the inner end of the slot F'. A tapered key K is inserted 80 in the slot F'', and passes through the hammer and through the open curve at the end of the handle. This key may be driven in until it slightly expands the curved portion of the handle, and thus binds the handle 85 firmly in the socket in the hammer; and it is evident that by this device the hammer may be adjusted in any desired position within the limits of its angle of oscillation about the end of the handle. This adjustment is of 90 great importance, as it is absolutely necessary that the two parts f f' of the two-part die make perfect contact when the hammer is brought down upon the anvil or head of the standard. By means of the construction 95 shown this contact is readily secured, as the key K may be loosened and the hammer pressed down upon the anvil until the faces of the dies are in perfect contact, when the key may be tightened and the hammer thus 100 secured upon the handle in exactly the desired position. A second adjustment of great importance is secured by the connection of the bracket B and standard A. The

neck *a* of the standard being cylindrical, the bracket may be swung about the vertical axis of the neck, in order to avoid any twisting of the two parts of the die with reference to each other, the bracket being secured in any desired position by means of a clip *b'*, passing about the two arms of the bracket at a point close up to the standard. In addition to the adjustments provided for, as already set forth, it is sometimes necessary to vary the distance of the hammer from the block *D*, which supports it, and also to rotate the handle slightly in its supporting-block. These movements are provided for by the means illustrated in Figs. 4 and 5, the ends of the two members of the handle being swaged on a slightly-tapered mandrel and seated in a corresponding socket in the block *D*. A plug *P* lies between the two arms and may be moved longitudinally by means a bolt *P'*, provided with a nut *P''*, engaging the end of the bolt and resting against the outer face of a cap or washer *W* on the rear end of the block. By means of the bolt and nut the plug *P* may be drawn outward, so as to tighten the arms within the socket, and thus fasten the handle in any desired position with reference to the block. These various adjustments—viz., of the bracket with reference to the standard, the hammer with reference to the handle, and the handle with reference to the block—provide completely for the perfect contact of the two members of the two-part die.

Between the ends of the downwardly-extending arms *c'* of the head *C* is pivoted a transverse bar *G*, provided with a forward-extending arm *G'*, whose free end is connected by means of a link *L* with a point on the head *D* slightly below and in front of the axis of oscillation of the head. On the bar *G* is formed a block *G''*, in which is secured the upper end of the lever *M*, adapted to operate the hammer. This lever might be formed upon or attached directly to the bar *G*; but I prefer to secure it in the block *G''* in substantially the manner illustrated in Fig. 6, in which *R* is a channel or recess extending longitudinally through the block and somewhat broader than the lever *M*, which lies in the channel and is secured by means of a pivot *p*, passing through the block and lever. Rubber buffers *g* are set in the block near its front end and press against the upper and lower edges of the lever, and a clip *g'*, passing around the block, secures the rubber buffers and prevents their accidental displacement. The rubber buffers being interposed between the lever and the block take up the shock of the blow of the hammer and greatly lessen the strain upon the operator of the machine.

The hammer is held above the anvil in substantially the position shown in Fig. 1, by means of a spring or springs *S*, of any desired form, connecting the block *D* with the head *C* or with any other stationary portion of the

machine, and downward pressure upon the free end of the lever *M* overcomes the resistance of the spring and swings the hammer downward upon the anvil, the operation of the hammer in this respect being the same as that of foot-power hammers of any ordinary construction.

In the use of this hammer, as well as any other heavy forging-hammer, it is very desirable to keep the lower die free from scale, and as a foot-power hammer is frequently used in shops not provided with means for furnishing an air-blast, I have found it a great convenience to provide the machine with means for blowing the scale from the die. One simple and practical form of device for this purpose is shown in Fig. 1, in which *T* is a cylinder of an ordinary air-pump, fastened by any suitable means to the standard *A*, and *T'* is the piston-rod of the pump, extending downward from the cylinder and provided at its lower end with a horizontal arm extending across and above the lever *M*, at a point near the end thereof. The piston may be forced downward by a spring, either within or without the cylinder, and the lever *M* at each upward movement strikes the extension at the lower end of the piston-rod and forces the piston upward, the air within the cylinder being expelled through a pipe *t*, extending upward from the cylinder, and having its upper end so bent as to direct the current of air across the face of the die *f'*. Any simple form of pump or bellows may be substituted for the one illustrated and described; but I have found in practice that a pump constructed substantially as shown, and without any great accuracy of fitting, works very satisfactorily and keeps the die practically free from scale and cinders.

Having now described and explained my invention, what I claim as new, and desire to secure by Letters Patent, is—

1. In a foot-power hammer, the combination, with a suitable standard adapted to receive one of the parts of a two-part die, of a hammer-supporting bracket supported by the standard and free to rotate about the same, and means, substantially as shown and described, for securing it in any desired position with reference thereto, substantially as and for the purpose set forth.

2. The combination, with the standard *A*, having the cylindrical neck *a*, of the bracket *B*, pivoted on said neck, and a clamp for securing the bracket in any given position with reference to the neck.

3. The combination, with the standard *A*, having the cylindrical neck *a*, of the bracket *B*, formed of a single bar bent at its center to conform to the neck *a*, the head *C*, rigidly fastened to the ends of said bar, and the clamps *b'*, encircling the arms of the bracket and adapted to clamp them in any desired position on the neck *a*, substantially as and for the purpose set forth.

4. In a foot-power hammer, the combination,

- with a rocking block, a spring for rocking it in one direction and a lever for rocking it in the opposite direction, of a hammer-handle having a hammer secured on its free end and 5 having its opposite end seated in said block, the end so seated in the block being susceptible of longitudinal and rotary adjustment therein, substantially as and for the purpose set forth. 7c
- 10 5. In a foot-power hammer, the combination, with a rocking block, a spring for rocking it in one direction and a lever for rocking it in the opposite direction, of a hammer-handle made up of two approximately parallel 15 members, one end of said handle being provided with a hammer and the other end being secured in said block, substantially as and for the purpose set forth. 75
6. The combination, with the rocking block 20 D, a spring for rocking it in one direction, and a lever for rocking it in the opposite direction, of the handle E, made up of two parallel members having ends inserted in a conical socket in the block D and shaped to conform to the surface thereof, a plug P, lying between the ends of said members and within said socket, and a bolt and nut P' P'', adapted to adjust said plug, and thus to clamp said ends in said socket, substantially as and for 25 the purpose set forth. 8c
7. In a foot-power hammer, the combination, with a rocking block, a spring for rocking it in one direction, and a lever for rocking it in the opposite direction, of a hammer-handle set in said block and a hammer secured on the free end of said handle and susceptible of limited angular adjustment in the plane of oscillation of the handle. 90
8. The combination, with a hammer having 40 a socket formed in one of its faces, of a handle made up of two members and having its end seated in said socket, and a key passing transversely through said hammer and between the members of said handle and adapted 45 to press said members against the walls of said socket, and thereby bind the end of the handle securely therein, substantially as and for the purpose set forth. 100
9. The combination, with a hammer F, 50 formed with a socket F', having its inner end curved, substantially as shown, of the handle E, made up of a single bar of metal bent at its center in a curve e, inserted in said socket and conforming to the curved surface thereof, and a key K, passing transversely through 55 said hammer and within the curved end of said handle, said key being adapted to expand said curved portion and bind the same within the socket, substantially as and for 60 the purpose set forth. 105
10. In a foot-power hammer, the combination, with a rocking block, a hammer-handle, the hammer supported thereby, and a spring for rocking said block and hammer in one 65 direction, of an oscillating block connected 110 with said rocking block by suitable levers, an operating-lever seated loosely in a channel in said oscillating block and pivoted at one point therein, and rubber buffers interposed between the edges of said lever and the walls of said channel and forming an elastic connection between said lever and said block, substantially as and for the purpose set forth. 115
11. The combination, with the oscillating block G', formed with the channel R, of the lever M, having one end loosely seated in said channel, the pivot p, passing through the block and through the lever at a point near its end, the rubber buffers g, interposed between the edges of the lever and the walls of the block, and the clip g', encircling said block and securing said buffers in place, substantially as and for the purpose set forth. 120
12. The combination, with the rocking block D, the hammer-handle, and hammer supported thereby, and a spring for raising said hammer, of the oscillating bar G, lying below said block D and formed with a forward-extending lever G', the link L, connecting the free end of said lever G' with a point on the block below and in front of its axis of oscillation, and a lever M, rigidly connected with said bar G and adapted to operate the same, substantially as and for the purpose set forth. 125
13. In a foot-power hammer, the combination, with a suitable base and a die attached thereto, a rocking hammer, and a lever adapted by its downward stroke to swing the hammer against the stationary die, of an air-pump provided with a discharge-tube directed toward the face of said die, a piston within said air-pump, and a piston-rod attached to said piston and adapted to be operated by the hammer-operating lever at each upward stroke thereof, thereby forcing a current of air against the face of said stationary die, substantially as and for the purpose set forth. 130
14. The combination, with the standard A and die f', of a rocking hammer, a spring for raising the same, an operating-lever M, connected with the hammer, the air-cylinder T, provided with the discharge-tube t, directed toward the face of said die f', and the piston-rod T', having at its end an extension lying across and above said operating-lever M, whereby at each upward stroke of said lever said piston-rod is forced upward, thereby expelling the air from said cylinder and forcing it through said discharge-tube against the face of said die, substantially as and for the purpose set forth. 135
- In testimony whereof I have signed this specification in the presence of two subscribing witnesses. 140
